UNITED STATES PATENT OFFICE

HENRY B. JENNINGS, JR., OF LEESBURG, VIRGINIA

LOOSE-LEAF BINDER

Application filed November 1, 1928. Serial No. 316,471.

This invention relates to improvements in temporary binders, or loose leaf sheet holders.

The principal object of this invention is to provide means for holding a single sheet of paper as well as an entire pack, or any intermediary quantity between a single sheet and an entire pack. Heretofore it has been practically impossible to so adjust the holders that a single sheet of paper can be securely held, and under the same conditions, permit insertion of a large quantity of paper. In my arrangement, a single sheet of paper can be just as securely held as an entire pack.

Another object is to provide an improved ratchet adjusting mechanism for locking the halves of the binder in desired position.

Still another object of the invention is to provide an improved loose sheet holder structure.

Other objects will appear from the detailed description thereof.

In the drawings:

Figure 1 is a perspective of the binder with the side members broken away so as to expose the interior of the binder, which is positioned to hold a single sheet of paper;

Figure 2 is a perspective with the wings folded back to receive a large quantity of paper;

Figure 3 is a perspective showing the two halves of the binder separated for the insertion of paper;

Figure 4 is an end elevation of the binder showing the toggle member in unbroken position;

Figure 5 is a detail section taken along line 5-5 of Figure 4, showing the locking mechanism in corresponding position;

Figure 6 is an end elevation showing the toggle broken and the halves of the binder in locked position;

Figure 7 is a section taken along line 7-7 of Figure 6 showing the toggle in locked position;

Figure 8 is a section showing the wings in position and holding a single piece of paper, with toggle unbroken;

Figure 9 is a section showing a large amount of paper secured in the binder;

Figure 10 is a section on the line 10-10

of Figure 7 showing the ends of the springs engaging the ratchet member:

Figure 11 is a detail section on the line 11-11 of Figure 5 showing the thumb screw in relation to the outer face of the housing;

Figure 12 shows the upper and lower half of the U-shaped locking members of the binder, the covering being removed; and

Figure 13 is a modification of the toggle locking means.

Referring to the drawings in which similar reference characters refer to similar parts throughout the several views:

Numeral 1 designates a loose leaf book binder comprising a pair of covers 2 and 3 which overlap each other at the back. The pair of covers 2 and 3 have base plates 4, usually made of metal, bent in a longitudinally L-shaped manner to form the overlapping ends and covered with material 5. Secured to the base plate 4 of cover 2 is a broad flat strip of metal 6 with its ends 7 bent at right-angles and toothed at their side edges, and secured to cover 3 is a similar member 8 having housings 9 at the ends to receive the toothed ends 7.

The base portions of housings 9 are turned so as to form securing means 10 for the U-shaped wires 11, the free ends of which extend upward parallel to the housings 9 and are connected by toggles 12. The locking pins 13 of the toggles 12 slides in slots 14 in the outer face of the housings 9 and project to the inner face of walls of the housings 9,

so that when the toggle is broken downward the ends of wires 11 will be pulled into ratchet teeth 15 in the ratchet ends 7. Thumb portions 25 of the locking pins 13 of the toggle have their inner flattened heads 26 slide in the slots 14. When the toggles are pushed upward so that the same locking pins are slightly above the ends of the toggles at the top of the housing 9, the wires 11 will be pushed from the ratchet teeth 15 and the locking pins 13 will seat in notches 17 directly above the notches 16, whereupon the thumb portions 25 may be turned into locked position.

Secured to the U-shaped members 6 and 8 are wing members 17 which are pivotally

connected to the members 6 and 8 by means of hinges 18. The wing members 17' are L-shaped one edge forming the hinged portion and the other side adapted to back against the covers 2 and 3 when in inoperative position and forward against posts 22 when in operative position. These hinges are formed of tongues of metal 19, which are taken from the respective members 6 and 8, passed through openings 20, in the wing members 17' and bent around to form a hinge. Posts 22 are supported by the U-shaped members 6 and 8 and have shoulders 23 formed thereon by flattening the outer portions of the posts so that the wing members 17' which have corresponding cut-out portions 27, may be supported by said shoulders, when the wings 17' are in use.

When not in use, the wings will be folded back out of the way and held in such position by the placing of paper on the posts. The two members 6 and 8 support posts 22 in staggered relation, when the covers are brought together, as well as the wing members 17'. Opposite the posts 22 are openings in the respective members 6 and 8 to receive the respective posts. Rivets 24 pass through the cover 2 and 3 to secure the U-shaped members to the base plates.

Figure 13 shows a modified form wherein is used instead of the toggle as shown in the other figures, a straight bar 28 secured at one end to one of the U-shaped wires 11, the other end having a shoulder 29 which bears against the other leg of the U-shaped wires to force the same out of engagement with the ratchet teeth when the bar is horizontal and permits the wire to spring into engagement when the bar is lowered.

As actually used, the paper is placed upon the posts of the cover having the housings at its ends, the other cover containing the ratchet members being fitted into the housings, the toggle members previously having been locked in parallel position or in unbroken position.

After the top cover has been forced down upon the paper, the toggle will be broken downwardly to the lower notch, and the locking pin turned, the wire members being forced into the ratchet teeth opposite the respective ends and securely locking the two halves together.

Should it be desired to remove the paper from the binder, the thumb portion is turned a quarter turn and the locking pins raised to the upper notch, the thumb portion turned to lock the same against accidental displacement, and the upper half of the cover lifted from the lower half which permits the removal of the paper or any proportion thereof. If it is desired to secure a single sheet of paper, or a limited amount of paper, in the binder, the wings 17' are folded over against the posts in each cover, so that the

wings come to rest on the shoulders on the posts. The paper is then placed in the cover containing the housing, and the same operation disclosed above is repeated. The two planes of the wings in the respective covers will be placed as closely adjacent each other as possible, regulated by the adjustable ratchet and toggle mechanism, only the thickness of the varying quantities of paper separating the two. This permits of a single piece of paper being held just as securely as a larger amount. When a large pack of paper of an inch or more thickness is desired to be placed in the binder, the wings may be folded back parallel to the back of the halves as shown in Figure 9 and the full quantity placed on the posts. Without the use of the wings, it is impossible to hold a single sheet of paper tightly in place or an amount of paper of less thickness than the depth of one of the covers, which causes the paper thus held to become dislodged and torn from the posts which is a very undesirable condition.

When the modified form of fastener is used, as shown in Figure 13, the bar is raised when it is desired to place the paper on the posts which forces the ends of the U-shaped wire outward and permits the placing of the ratchet member in the housing. Upon the free end of the bar being lowered, the ends of the U-shaped wire will spring inwardly, engaging the space between the opposite ratchet teeth and thus locking the two halves of the binder together.

What I claim is:

1. A loose leaf binder comprising separate covers, one cover having locking means at its ends, the other cover having means at its ends to fit into the first-mentioned locking means and means carried by the first-mentioned cover for operating said locking means, and other means for locking said locking means in operative and inoperative position.

2. A loose leaf binder comprising separate covers, one cover having housings secured at each end, a U-shaped spring member secured at the lower extremity of each housing, the U-shaped members having legs extending parallel to the sides of the housing, the ends of the legs bent over the top of the housing, the other cover having a toothed member secured at each end, said members being capable of fitting into said housings, and means secured to said legs for forcing said legs into and out of engagement with said toothed member.

3. A loose leaf binder comprising separate covers, one cover having housings secured at each end, said housings having a slot extending the height of the housing, a U-shaped spring member secured at the lower extremity of each housing, the U-shaped members having legs extending par-

allel to the sides of the housing, the ends of the legs bent over the top of the housing, a toggle connecting the ends of each U-shaped spring member, and including a locking pin forming the pivotal point of said toggle and sliding in said slot, the other cover having a toothed member secured at each end thereof said members being capable of fitting into said housings, said toggle forcing the legs of said U-shaped member into and out of engagement with said toothed member.

4. A loose leaf binder comprising separate covers, one cover having housings secured at each end, said housings having a slot extending the height of the housing, a U-shaped spring member secured at the lower extremity of each housing, the U-shaped members having legs extending parallel to the sides of the housing, the ends of the legs bent over the top of the housing, a toggle connecting the ends of each U-shaped spring member, and including a locking pin forming the pivotal point of said toggle and sliding in said slot, said locking pin and groove being adapted to secure said toggle in broken and unbroken position.

5. A loose leaf binder comprising separate covers, one cover having locking means at its ends, the other cover having cooperating locking means at its ends to fit into the first-mentioned locking means, and a toggle connecting the first-mentioned means for locking and unlocking the two covers in their relative positions.

6. A loose leaf binder comprising separate covers, locking means at the ends of each cover to secure the two covers together, members secured to each cover intermediate the locking means, paper-receiving means projecting from said members, and wings pivotally connected to said members and movable relative to the last-named means to form thereupon secondary paper-supporting means.

7. A loose leaf binder comprising a cover, adjustable locking means at the ends of the cover, members secured to the upper and lower portion of the cover intermediate the locking means, paper-receiving means projecting from said members and wings pivotally connected to said members and movable relative to the last-named means to form thereupon secondary paper supporting means.

8. A loose leaf binder comprising separate covers, locking means at the ends of each cover to secure the two covers together, members secured to each cover intermediate the locking means, posts projecting from said members to receive paper, and wings pivotally connected to said members and movable relative to said posts to form thereupon a secondary paper supporting member.

9. A loose leaf binder comprising sepa-

rate covers, locking means at the ends of each cover to secure the two covers together, members secured to each cover intermediate the locking means, posts projecting from said members to receive paper, wings pivotally connected to said members, said posts having shoulders to form rests for said wings, said wings movable relative to said posts to form thereupon secondary paper supporting members.

10. A loose leaf binder comprising separate covers, locking means at the ends of each cover to secure the two covers together, members secured to each cover intermediate the locking means, posts projecting from said members in staggered relation with each other when in locked position, wings pivotally connected to said members and movable relative to said posts to form thereupon secondary paper-supporting members.

11. A loose leaf binder comprising separate covers, locking means at the ends of each cover to secure the two covers together, members secured to each cover intermediate the locking means, posts projecting from said members, wings pivotally connected to said members, said wings having indents to receive said posts, said posts having shoulders to form rests for said wings, said wings movable relative to said posts to form thereupon secondary paper-supporting members.

12. A loose leaf binder comprising separate covers, locking means at the ends of each cover to secure the two covers together, members secured to said covers intermediate the locking means, posts projecting from said members to receive paper, wings pivotally connected to said members, either wing capable of folding into position against the respective posts to form thereupon a secondary paper-supporting member.

13. A loose leaf binder comprising separate covers, locking means to secure the two covers together, means between said covers to receive and support paper, and wings pivotally connected to said means and movable relative thereto to form secondary paper supports.

14. Clamping means for paper comprising two spaced main clamping members relatively adjustable with respect to each other down to a determined minimum distance apart, and auxiliary clamping members swingably mounted between the main clamping members and when in operative position substantially bridging the minimum space between said main clamping members, said auxiliary clamping members being swingable to inoperative position, leaving the space between said main clamping members substantially unobstructed.

15. A loose leaf binder comprising separate covers, one cover having housings at its ends, the other having notched members slideable in said housings, substantially parallel

spring elements adjacent said housings operably positioned with respect to said notched members and normally engaging the notches of said members, and means for spreading said spring elements to release the notched members.

In testimony whereof I affix my signature.

HENRY B. JENNINGS, JR.
